Patented June 1, 1915.

UNITED STATES PATENT OFFICE.

SADIE WIDEMAN, OF NILES, MICHIGAN.

CAR-SIGNAL.

Specification of Letters Patent. Patented June 1, 1915.

1,141,509.

Application filed July 31, 1911. Serial No. 641,451.

To all whom it may concern:

Be it known that I, Mrs. SADIE WIDEMAN, a citizen of the United States, residing at Niles, in the county of Berrien and State of Michigan, have invented certain new and useful Improvements in Car-Signals, of which the following is a specification.

This invention relates to improvements in car signals and the principal object is to provide a device for signaling to the motor-man of an approaching car that a passenger desired to get on.

Another object is to provide a device which is adapted to be secured to a convenient telegraph or trolley pole at a crossing, said device having a signal which can be exposed to view by a manually operating means within convenient reach of the prospective passenger.

Other objects and advantages will be apparent from the following description and with particular reference to the accompanying drawings.

In the drawings:—Figure 1 is a side elevation of the device mounted on the pole adjacent the single track railway. Fig. 2 is a similar view showing one of the doors of the device open. Fig. 3 is a vertical section on the line 3—3 of Fig. 1, slightly enlarged. Fig. 4 is a plan view showing the same when used in connection with a double track railway. Fig. 5 is a plan view of the device shown in Fig. 1.

Referring to the drawings 10 represents a trolley or telegraph pole which is located along the side of a railway track and to which is secured the box 11 by means of the brackets 12.

On each side of the box is a door 13 held normally closed by the spring hinges 14.

Secured to the doors at points 15 are the chains 16, which extend in the direction of the pole 10, and over the pulleys 19 on the pole, the lower end of each of said chains 16 having a handle 20 secured thereon.

Mounted in any convenient point within the box is an incandescent bulb 21, preferably of red glass, said bulb receiving cur-

rent from the mains 22 by means of the feed wires 23.

On the inner face of each of the doors 13 is a mirror or other reflector 11' which is to reflect the light of the lamp when the opposite door is opened.

The box extends outwardly from the post in the direction of the track, and on the side of the track and of the crossing where the car should stop, so that a person at night, desiring to signal to an approaching car that he desires to get aboard, simply pulls the handle 20 which opens one of the doors 13, and exposes the red lamp 21 to view from the side of the box toward the approaching car.

In double track railways I place the box on the trolley pole between the tracks, and have each of the chains 18 to extend through the pulleys 25 on the ends of the bar 24 to the sides of the track, so that the signal may be exposed by a passenger from either side, it being only necessary for the prospective passenger to position himself where the car is to stop, and upon the approach of the car operate the chain 18 to open one of the doors and cause the light of the lamp to be reflected from the opposite door.

What is claimed is:

A signaling device for electric railways comprising an inclosing box mounted on a suitable support, a source of light within the box, horizontally swinging spring held doors on opposite sides of the box and arranged to open toward an approaching car, reflectors on the inner faces of the doors, and means for opening the doors, whereby when one of the doors is opened the light within the box will be visible through the opening of the box and reflected from the reflector of the other door through the opening.

In testimony whereof I affix my signature, in the presence of two witnesses.

MRS. SADIE WIDEMAN.

Witnesses:

ENOLA ELDER,
HARRY C. LOCKARD.
